ELEVATOR TOILET SEAT FOR INVALIDS

T. Eric Aldred, 1105 8th Ave., Albany, Ga. 31707

Filed Dec. 18, 1972, Ser. No. 316,131

Term of patent 14 years

Int. Cl. D23—02

U.S. Cl. D23—71

FIGURE 3

FIGURE 4

FIG. 1 is a perspective view of an elevator toilet seat for invalids embodying my new design;

FIG. 2 is a top plan view thereof;

FIG. 3 is a side elevational view taken from the left side of FIG. 2;

FIG. 4 is a front elevational view thereof;

FIG. 5 is a side elevational view taken from the right side of FIG. 2; and

FIG. 6 is a rear elevational view thereof.

I claim:
The ornamental design for an elevator toilet seat for invalids, as shown.
